UNITED STATES PATENT OFFICE.

ANDREW C. PORTER, OF SENATOBIA, MISSISSIPPI.

BALING-PRESS.

SPECIFICATION forming part of Letters Patent No. 281,894, dated September 11, 1883.

Application filed July 7, 1883. (No model.)

To all whom it may concern:

Be it known that I, ANDREW C. PORTER, a citizen of the United States of America, residing at Senatobia, in the county of Tate and State of Mississippi, have invented certain new and useful Improvements in Baling-Presses; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to baling-presses; and it consists of the improved construction, fully described hereinafter, whereby the baling operations are greatly improved and facilitated, the pressing-follower readily shifted to permit the introduction of additional material, and the general construction of the machine improved and strengthened.

In the accompanying drawings, Figure 1 is a front elevation of a baling-press constructed in accordance with my invention. Fig. 2 is a side elevation of the same. Figs. 3, 4, 5, 6, and 7 are detail views.

On a suitable base, A, are mounted four standards, B B', having secured between them cross-bars C D, and forming the frame of the baling-box E and supply-box F. Two vertical shafts or rods, G G', are arranged on each side of the boxes E F, and are threaded in different directions. These shafts G G' pass through threaded perforations *a a'* of nuts *b b'*, which are secured at each end of a follower, H, by means of clamp-plates *c c'*, which rest on each side of said nuts *b b'* in grooves *d*, formed therein, and bolted to tenons *e* of the follower by bolts *e'*. Perforated lugs *f* on the upper face of the clamp-plates are adapted to receive the threaded ends of a tie-brace, *f'*, secured by nuts *f''*, so as to additionally strengthen the follower. The lower end of each shaft G G' passes through an elongated opening therefor in the base A, and through an open-ended slot, *i*, of a plate, I, bolted on the under side of said base, and carries near its lower end, *g*, a cog-wheel, J, the upper face of the hub *h* of which is convex, as shown in

Figs. 1 and 2, and rests in a concavity formed in the lower face of the plate I. The said plate I is provided with a curved lug, *j*, located at the end of the slot *i* of said plate, which lug partially encircles the lower end of the threaded shaft when said shaft occupies its normal position in the slot. Each of the ends *g* of the threaded shafts forms a tenon which bears in a mortise, *g'*, therefor in a bearing-block, K, cut away on its under side to straddle a horizontal shaft, L, turning in bearings *l* of hangers *l'*, depending from the under side of the base, and said horizontal shaft L has pinions *l'* keyed thereon and meshing with the cog-wheels *J*, and arranged to revolve said cog-wheels in different directions when turned.

Near the end of the horizontal shaft L is mounted a drive-pulley, M, keyed thereon, and on each side of said drive-pulley are mounted idler-pulleys M' M''. The idler-pulley M' is driven by a belt, N, from any suitable source of power, and the idler-pulley M'' by a cross-belt, N', from the same source, but in a different direction.

Two belt-shifters located above and below the pulleys M M' M'' consist each of a rod, O, one end, *o*, of which plays through a perforation near the end of a standard, O', which standard carries the end bearing, *o'*, of the shaft L. Each shifting-rod O is provided with two pins, *o' o''*, between which rest the belts N N'. The end *o'* of each shifting-rod O is connected to one end of a bell-crank lever, P P', pivoted, respectively, to the frame of the press, above and below the base A thereof, and to the other end of each of said bell-crank levers is secured a vertical rod, Q Q', which extends up above the top of the frame. The rod Q carries a bar or arm, *q*, located on said rod, near the top of the baling-box E, and extending from the rod Q, at right angles thereto, so as to be struck by the follower when it in its descent arrives at the top of the baling-box. The rod Q' is also provided with an arm, *q'*, which is connected to said rod Q'', near the top of the same, above the follower.

The operation of the press is as follows: The chambers E F having been filled with material to be baled, the belt is moved from the idler-pulley M' to drive the pulley M, so as to. 100

revolve the shaft L and its pinions τ , which impart motion to the cog-wheels J J and vertical shafts G G', provided, respectively, with right and left screw-threads and revolved in different directions. The revolution of the said shafts G G' causes the follower H to descend, by reason of the nut-connection therewith, and compress the material of the two chambers within the area of the baling-chamber E, thus forming the body of the bale. As the said follower, in descending, arrives near the top of the baling-chamber, it strikes the arm q of the vertical rod Q, moving the latter to depress the end of the bell-crank lever P, to which it is connected, thereby throwing out the other end of said lever to move the rod O, thus shifting the belt N from the fixed pulley M back to the idler-pulley M'. The arm q' of the rod Q' is now depressed, so as to move the said rod, its bell-crank lever P, and shifting-rod O, to shift the cross-belt from the idler-pulley M² to the pulley M and cause the threaded shafts G G' and intermediate gearing to revolve in a reverse direction, resulting in the ascent of the follower H, which, as it arrives at the top of the press, comes in contact with and raises the arm q' of the rod Q', so as to shift the cross-belt N' back onto the idler-pulley M², causing the movement of the follower to be arrested slightly above the top of the press-frame. As the lower ends of the shafts G G' bear in the bearing-boxes K and pass through slots in the plates I and base A, the said shafts G G' and boxes K can be tilted on the horizontal shaft L, enabling the follower to be moved to one side of the press, as clearly shown in Fig. 2, to permit the introduction of material in the chambers E F. The convex faces of the hubs h of the gear-wheels move in the concavities on the under side of the plates, affording no obstruction to the movement of the hubs when the same are tilted. The curved lugs j of the plates I act as stops to limit the movement of and brace the shafts G G' in the slots.

The panels composing the sides of the baling-chamber are made removable in any of the well-known ways to permit the removal of the bales from said chamber.

By having the screw-threads on the shafts G G' in different directions, the strain on the said shafts and their driving mechanism is equalized, and derangement of parts prevented.

It will be seen that the machine described is positive and automatic in operation, the baling operations facilitated, and the general structure of the machine rendered durable and simple.

I do not limit myself to the precise construction shown and described, as the same may be subject to modification and change without departing from the spirit of the invention.

I claim—

1. The combination, in a baling-press, of a baling and supply chamber, vertical shafts arranged at each side thereof, and threaded in different directions and passing through slotted openings in the base of the press-frame, and plates I, bolted thereto and terminating in a tenon bearing in a mortise formed in a bearing-block straddling one of the shafts of the mechanism for revolving said threaded shafts, substantially as set forth. 60

2. The combination, in a baling-press, of a baling and supply chamber, vertical shafts arranged at each side thereof, and threaded in different directions and passing through slotted openings in the base of the press-frame, and slotted plates I, bolted to the latter, 70 and provided with the lugs j , bearing-blocks receiving the lower end of each shaft and straddling the horizontal shaft L, and devices for rotating the threaded shafts, substantially as described. 75

3. The combination, in a baling-press, of threaded vertical shafts G G', mechanism for revolving said shafts, a follower, H, nuts b b' , having grooves d , and clamp-plates c c' , resting in said grooves and secured to the follower by bolts e , substantially as set forth. 80

4. The combination, in a baling-press, of threaded vertical shafts G G', mechanism for revolving said shafts, a follower, H, and nuts b b' , secured to the follower by means of clamp-plates c c' , having ears or lugs f , perforated for the reception of the threaded ends of a tie-rod, f' , substantially as set forth. 85

5. The combination, in a baling-press, of threaded vertical shafts G G', carrying at their lower ends cog-wheels J J, a horizontal shaft bearing in hangers dependent from the base A of the frame, and carrying pinions τ τ' , meshing with the cog-wheels J, said shaft L carrying a fixed pulley, M, and idler-pulleys M' M², arranged on each side of the said fixed pulley, and carrying, respectively, straight and cross driving-belts, and devices operated from the follower to shift the belts alternately from the idler to the fixed pulley, substantially as set forth. 90

In testimony whereof I affix my signature in presence of two witnesses.

ANDREW C. PORTER.
